ATTORNEYS

UNITED STATES PATENT OFFICE.

JULIAN STRZYCKOWSKI, OF NEW YORK, N. Y.

LAMINATED WEAR-RESISTING COMPOSITION.

Application filed September 29, 1923. Serial No. 665,549.

To all whom it may concern:

Be it known that I, JULIAN STRZYCKOWSKI, a citizen of the United States, residing at New York, county of New York, and 5 State of New York, have invented certain new and useful Improvements in Laminated Wear-Resisting Compositions, of which the following is a specification.

The principal object of this invention is 10 to provide a new and improved construction of a composition of matter especially adapted for such uses as floorings, automobile tires and similar purposes where a material is required that will stand up under 15 hard and continuous usage.

Another object is to provide a laminated construction of metallic and fibrous material which will form a compact, but semi-resilient structure, in which the metallic elements 20 are constructed and arranged to act as a binder or connecting means for holding the fibrous elements joined together.

For the accomplishment of these and such further objects as will hereinafter be apparent to those skilled in the art to which this 25 appertains, the invention consists in the construction, combination and arrangement of parts herein specifically described and illustrated in the accompanying drawings, 30 wherein is shown a preferred embodiment of the invention, but it is to be understood that changes, variations and modifications may be resorted to which fall within the scope of the claims hereunto appended.

35 In the drawings forming a portion of this specification:

Fig. 1 is a plan view of a composition embodying my invention and

40 Figs. 2 and 3 are sections on the lines 2—2 of Fig. 1 and 3—3 of Fig. 2 respectively.

As shown in the drawings, my improved composition consists of a plurality of comparatively thin sheets 10 of a suitable semi-resilient substance such as fibre, wood, 45 paper, pressed pulp, rubber, canvas or the like. Between the sheets 10 a metallic structure 11 is arranged which is preferably of open mesh configuration as shown in Fig. 2 of the drawing. The strands 12 of the 50 metallic mesh are preferably flat as shown

and are formed into a diamond shape mesh, the flat faces of the strands being twisted to extend transversely of the sheets 10 between the pointed ends 13 and 14 of the diamonds. At the point of connection 15 of the 55 diamond shape meshes, the strands also extend transversely to the sheets 10. It will be noted that the diamond shaped meshes are arranged in staggered relation between the sheets 10 so that the central longitudinal 60 diagonals of the meshes of one metallic structure are in alignment with the points of connection 15 of the adjacent structure. By staggering the meshes of the metallic structure in this manner, the ends of the 65 metallic strands which project to resist the wearing strains are distributed more thoroughly and the binding or holding effect of the strands is also more evenly distributed.

After the sheets 10 and metallic structure 70 11 are assembled they are subjected to pressure which causes the flat strands 12 to be pressed into the adjacent sheets, thus causing the strands to perform an effective binding function and thereby hold the composition 75 in a compact unitary mass.

Having thus described my invention what I claim as new and desire to secure by Letters Patent is:—

1. A laminated wear resisting composition 80 consisting of a plurality of thin sheets of semi-resilient material and an open meshed metallic structure interposed between said sheets, said metallic structure formed of a plurality of interconnected flat 85 strands, the flat faces of which extend transversely of and are sunk into said sheets, to bind said sheets and metallic structure into a compact unitary mass.

2. A laminated wear resisting composition 90 consisting of a plurality of thin sheets of semi-resilient material and a plurality of an open diamond meshed metallic structures interposed between said sheets, the meshes of adjacent members of said metallic structures being arranged in staggered 95 relation.

3. A laminated wear resisting composition 100 consisting of a plurality of thin sheets of semi-resilient material and a plurality

of metallic structures interposed between said sheets, said metallic structures being formed of a plurality of flat strands interconnected to form open diamond shaped meshes, the flat faces of said strands extending transversely to and being sunk into said sheets to bind said sheets and struc-

ture into a compact mass, and the meshes of adjacent members of said metallic structures being arranged in staggered relation.

In testimony whereof I have affixed my signature.

JULIAN STRZYCKOWSKI.
